(57) **CLAIM**

The ornamental design for a glass shelf, as shown and described.

DESCRIPTION

FIG. 1 is a front perspective view of a glass shelf showing my design;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a right side elevational view thereof.

The broken lines in the Figures are for illustrative purposes only and form no part of the claimed design.
